228,832

BOOT

Edward G. Robinson, 6710 Whitney Ave.,
Cleveland, Ohio 44103

Filed Oct. 29, 1971, Ser. No. 194,098

Term of patent 3½ years

Int. Cl. D2—04
U.S. Cl. D2—275

Fig. 1

The figure is a front perspective view of a boot showing my new design, the other side being substantially similar thereto.

I claim:

The ornamental design for a boot, as shown and described.

References Cited

Boot and Shoe Recorder, March 1971, p. 5, shoe shown by Thomas Taylor & Sons.

Men's Wear, Jan. 10, 1964, p. 52, Boot shown 2nd from top on left and one 2nd from top on right.

The Sunday Star, Aug. 23, 1964, p. C 3, Boot by "Miss Amy," having laces.